CLAIM

The ornamental design for a tool for installing screen protectors as shown and described.

DESCRIPTION

FIG. 1 is a front, bottom, and left perspective view of a tool for installing screen protectors showing my new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, right perspective view thereof; and,

FIG. 9 is a rear, right perspective view of the use state of tool for installing screen protectors.

The aspects of the tool for installing screen protectors depicted by broken lines in FIGS. 1 and 2, form no part of the claimed design. The broken line showing of the cell-phone in FIG. 9 is provided for purposes of environment, and forms no part of the claimed design.
